Attorney

UNITED STATES PATENT OFFICE.

HARRY E. SHUMWAY, OF WATERFORD, NEW YORK, ASSIGNOR TO VAN ZANDT,
JACOBS & CO., OF TROY, NEW YORK, A CORPORATION OF NEW YORK.

FOLD-COLLAR.

1,243,452.

Specification of Letters Patent. Patented Oct. 16, 1917.

Application filed December 18, 1915. Serial No. 67,678.

To all whom it may concern:

Be it known that I, HARRY E. SHUMWAY, a citizen of the United States, residing at Waterford, county of Saratoga, and State 5 of New York, have invented certain new and useful Improvements in Fold-Collars, of which the following is a specification.

Reference may be had to the accompanying drawing, and the reference characters 10 marked thereon, which form a part of this specification. Similar characters refer to similar parts in the several figures therein.

The invention relates to fold-collars of various kinds, and is particularly adapted 15 for soft or unstarched fold-collars.

The principal object of the invention is to retain in proper position in use, the end-portions of the folded-over top of the collar.

Other objects will appear in connection 20 with the following description.

Figure 1 of the drawings is a front view in perspective of a fold-collar embodying my invention.

Fig. 2 is a similar view of a broken-away 25 front portion of the collar with the ends of the folded-over top unbuttoned and folded back to expose the long end of the band.

Fig. 3 is a view in elevation of an end-portion of the collar showing the inner side 30 of the long end of the band.

Fig. 4 is a view in perspective of the button-carrying tape whereby the end-portions of the folded-over top are secured together and also to the long end of the band.

35 Referring to the drawing wherein the invention is shown in preferred form, 1 is the band, and, 2, is the folded-over top, the band having a long end, 3, insertible between the band and folded-over top at the other 40 end of the collar.

The band has the usual buttonholes for attachment to the neckband of a shirt, including the usual front buttonhole, 4, in the long end of the band.

45 Symmetrically located on opposite sides of the front buttonhole, 4, are a pair of buttonholes, 5, formed in the long end of the band.

The end-portions of the folded-over top

are provided respectively with buttonholes, 6, coincident with the respective buttonholes, 5, in the long end of the band.

Back of the long end of the band is a link, 7, having near its respective ends buttons, 8, at a distance apart corresponding with the buttonholes, 5-5, in the long end of the band, which buttons are adapted to be inserted outwardly, one through one of the buttonholes, 5, in the band and the coincident buttonhole, 6, in the adjacent end-portion of the folded-over top, and the other through the other buttonhole, 5, in the band and the other buttonhole, 6, in the adjacent end-portion of the top coincident therewith.

When the link is thus buttoned to the band and top of the collar, as shown in Fig. 1, it is concealed back of the long end of the band and prevents the ends of the top from spreading apart, and also holds each end of the top closely to the band.

The link, 7, is preferably made separate from the collar and detachably connected therewith so that it can be removed from the collar while the collar is being laundered, thus avoiding destruction or loss of the buttons in the laundering operation.

The link, 7, may be made of tape or other suitable material; and the buttons, 8, may be attached thereto in any known manner.

By the term "buttons," I mean to include any of the usual forms of studs or buttons adapted for engagement with a buttonhole.

What I claim as new and desire to secure by Letters Patent is:

1. A fold-collar having a band, a folded-over top provided with buttonholes in its respective end-portions, said band being provided with usual means for detachably securing its ends together and to the neckband of a shirt, and with buttonholes coincident with the respective buttonholes in the end-portions of the folded-over top; and a link concealed by the band having buttons insertible outwardly through the respective coincident buttonholes in the band and end-portions of the folded-over top.

2. A fold-collar having a band with a long end provided with the usual front but-

tonhole and with a pair of other buttonholes symmetrically located on opposite sides of said front buttonhole; a folded-over top provided with buttonholes in its end-portions coincident with the respective symmetrically disposed buttonholes in the long end of the band; and a link extending back of the long

end of the band having buttons insertible through the respective coincident apertures in the long end of the band and the end-portions of the top.

In testimony whereof, I have hereunto set my hand this 11th day of December, 1915.

HARRY E. SHUMWAY.
